(57) **CLAIM**

The ornamental design for a rotor for multicopters, as shown and described.

DESCRIPTION

FIG. 1 is a top perspective view of a rotor for multicopters showing my new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a cross-section view of the rotor for multicopters taken along line 9-9 in FIG. 7;

FIG. 10 is a cross-section view of the rotor for multicopters taken along line 10-10 in FIG. 7; and,

FIG. 11 is a cross-section view of the rotor for multicopters taken along line 11-11 in FIG. 7.
